(57) **CLAIM**

I claim the ornamental design for a cap, as shown and described.

DESCRIPTION

FIG. 1 is a perspective view of my cap;

FIG. 2 is a left side elevational view thereof with the right side elevational view being a mirror image thereof;

FIG. 3 is a top view thereof;

FIG. 4 is a bottom view thereof;

FIG. 5 is a front view thereof; and,

FIG. 6 is a rear view thereof.

The broken lines shown in the figures are for illustrative purposes only and form no part of the claimed design.
